WILLIAM H. COLLIER, OF JACKSON, TENNESSEE

ANTIFREEZE RADIATOR FOR AUTOMOBILES

Application filed December 15, 1930. Serial No. 502,544.

This invention relates to radiators such as are used in connection with internal combustion engines of the water jacketed type.

Engines of this kind are in general use for operating automobiles and in the colder climates the radiators of such engines frequently freeze in cold weather unless special precautions are taken. Radiators for automobiles are usually kept filled with water and the freezing of the water commonly results in rupture of one or more of the thin radiator tubes or cells which provide the greater part of the radiating surfaces.

These radiators are provided with an upper chamber or header and a lower chamber or header, these two being connected by the thin walled circulating pipes or cells. Under running conditions the lower header, the connecting structure and a portion of the upper header are kept filled with water much of which is held in the lower header.

Among the objects of the present invention are to provide a radiator of improved construction wherein the water will be automatically drained from the tubes or cells of the radiator when the temperature of the water approaches the freezing point; to provide for varying the effective volume of the lower header inversely with the temperature so that the water space within the lower header increases as the temperature of the contained water decreases and decreases as the temperature increases; to provide within the lower header, a contractile and expansible element for thus varying the effective volume of the header; and to so construct the lower header as to delay the loss of heat from the water contained therein.

With the above and other objects in view one embodiment of the invention will now be described in detail, reference being had to the accompanying drawing, wherein:—

Figure 1 is a perspective view showing a radiator as constructed in accordance with this invention and also showing one form of connection between the radiator and the water jacket of an internal combustion engine.

Figure 2 is an enlarged vertical section through the radiator and showing the condi-

tions existing when the temperature is normal.

Figure 3 is a view of the radiator in section on the same plane as Figure 2 but showing the conditions existing when the water has cooled to near the freezing point.

As here shown the radiator includes an upper header 10 having a filling cap 11. A lower header 12 having a double wall 13 forms the lower end of the radiator, the double wall providing an air space around the contents of the header and thus acting as a heat insulator to retard heat losses by the contained water. Radiator elements 14, which may be the usual cellular type, connect the headers to permit flow of water from the upper header to the lower header and are arranged to provide for cooling the water in its downward passage. One or more thermally controlled longitudinally expandable chambers of the type sometimes called sylphon bellows or tubes. I have therefore referred to these expansible chambers as sylphon elements. Each sylphon element constitutes a temperature controlled contractile and expansible means varying in volume directly as the variation in temperature of the water in the radiator. The size of the lower header is, for all practical purposes, the same at all temperatures but its effective volume, i. e. the space for water within the header, varies inversely as the temperature, since increase of temperature increases the space occupied by the sylphon element or elements and decrease of temperature decreases such space. In order to assist in the expansion and contraction of the sylphon element, it preferably contains a small quantity of some highly volatile liquid such as benzine.

An engine 16 has the usual water jacket which is connected by a pipe connection 17 with the upper header 10. A second pipe connection 18, having a pump 19 interposed in its length, connects the lower header with the water jacket. This connection 18 is so formed as to extend up to the top of the water jacket and then down to the inlet of the water jacket thus forming a goose-neck connection 18a. In order to prevent the action of the sylphon element from affecting the wa-

- ter in the water jacket by siphoning it off through the connection 19, a small by-pass tube 20 connects the upper point of connection 18 with the pipe connection 17, this 5 destroying any sylphonic action by the pipe connection 18. A check valve may be included in the connection 18 to prevent back flow instead of employing the goose-neck connection for this purpose.
- 10 The operation of the invention is clearly illustrated in Figures 2 and 3. In Figure 2 it will be seen that, at normal temperature, the sylphon element 15 is so expanded that much of the volume within the lower header 14 is occupied by the sylphon element or elements and the water is maintained at the normal or proper level. Upon the temperature dropping, as for instance when the engine is stopped, in cold weather, the water 15 in the radiator cools until the freezing point is approached. This causes the sylphon element to contract until it occupies but a small space in the lower header which then has 20 space enough around the sylphon element to allow all the water in the tubes 14 and upper header to flow down into the lower header as shown in Figure 3 where its remaining heat is conserved by the double walled or other insulating construction. Obviously, as 25 soon as the temperature around the sylphon increases when the engine is started, the sylphon element expands and the water will be forced up into the tubes 14 and upper header.
- 30 35 The advantages which are derived from this invention in addition to the protection from freezing will now be apparent. When starting the motor on a cold morning the engine and water in the jacket will heat more quickly because the radiator does not function to cool the water until the water in the jacket has become heated and that which flows down from the upper header has caused the sylphon element to expand and force the 40 water up to the normal level.
- 45 It will be evident to engineers that various other arrangements may be made embodying this invention. For example the sylphon element may be placed in an auxiliary insulated chamber connected to the radiator.
- 50 I claim:
1. A radiator of the class described provided with heat radiating elements, and a water storage chamber communicating with the heat radiating elements of the radiator and being provided with means for varying the effective volume inversely with the temperature, the maximum volume of said chamber having a capacity sufficient to hold substantially all of the water in the radiator.
